UNITED STATES PATENT OFFICE

160,177

PITCHER OR THE LIKE

Alexander O. Kirman, New York, N. Y., assignor to Thermoplex International, Inc., New York,
N. Y., a corporation of New York

Application October 27, 1949, Serial No. 5,736

Term of patent 14 years

(Cl. D44—21)

To all whom it may concern:

Be it known that I, Alexander O. Kirman, a citizen of the United States and resident of the city, county, and State of New York, have invented a new, original, and ornamental Design for a Pitcher or the like, of which the following is a specification, reference being had to the accompanying drawing, forming a part thereof, wherein:

Fig. 1 is a top plan view of a pitcher or the like, showing my new design.

Fig. 2 is a side elevational view thereof.

I claim:

The ornamental design for a pitcher or the like, substantially as shown.
